UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 30, 1923. Serial No. 648,705.

This invention relates to manifolding typewriting machines of the continuous billing type in which a continuous composite web is fed around a cylindrical platen, the composite web comprising several plies of work-sheets having successive corresponding forms printed thereon, said plies being sometimes separated from each other and sometimes joined at their side edges to form a fan-folded web, the various plies having carbon-sheets interleaved therebetween. The invention relates more particularly to means to facilitate the relative displacing or shifting between the carbon-sheets and the work-sheets, or, in other words, the shifting of the carbon-sheets from the typed set of forms to a fresh set of forms. The invention further relates to means for determining the relative shifting between the carbon-sheets and the work-sheets.

In the Underwood continuous billing machine, shown in the patent to Wernery and Smith, No. 1,132,055, dated March 16, 1915, in which a cylindrical platen is employed, it has been the practice to displace the platen upwardly by means of a swing frame, to permit the composite web to be straightened out preparatory to displacing or shifting the carbon-sheets along the work-sheets to a fresh set of forms. There is also employed in said machine a table extending rearwardly from the platen upon which a carbon-carrier is mounted to travel back and forth towards and away from the platen, said carbon-carrier having the ends of the interleaved carbon-sheets connected thereto, and said carbon-carrier being movable rearwardly by a handle while the work-sheets are drawn forward to a suitable gage.

An object of the present invention is to facilitate the relative shifting of the carbon-sheets and the work-sheets without lifting the platen; the platen remaining in the present invention always in the usual typing position. To this end, the carbon-carrier is not mounted on a table, but is pivotally supported at the rear of the carriage and connected to travel therewith, said carbon-carrier occupying normally a vertical position behind said carriage and being swingable rearwardly and downwardly to a substantially horizontal position after the feed-rolls have been released to withdraw the web around the platen to free it from said platen and bring that portion of the web including

the carbon-sheets to a straightened-out inclined position, in which position the leading edges of the work-sheets may readily be grasped, so that they may be shifted relatively to the carbon-sheets by drawing them forwardly to a suitable gage.

Another object of the invention is the provision of means to retain the carbon-carrier in its operative position, and thus prevent the forward slipping of the carbon-sheets while the work-sheets are being shifted relatively thereto, said means being also effective to hold the carbon-carrier in its normal upright position, so as to prevent it from falling forwardly or rearwardly from this position accidentally. To facilitate the forward and rearward movement of the carbon-carrier, provision is made of means comprising a relatively fixed handle, which may be pivoted on the machine frame, said handle being effective to actuate a swinging frame or bail to which a frame supporting the carbon-carrier is slidably connected, so that the carbon-carrier may travel back and forth relatively thereto with the typewriter carriage.

A knife is provided which is connected to the gage, so that it and the gage may be moved from their ineffective positions to their effective positions simultaneously either by moving the gage-bar itself or by means of a finger-piece associated with the knife.

According to the present invention, slack is produced in the composite web when the carbon-carrier is swung up to its normal position after a sheet-gaging and severing operation, this slack permitting the composite web to be readily re-inserted around the platen and also eliminating any resistance offered to the feeding movement of the composite web around the platen during the regular line-spacing operations, thus avoiding any possibility of slippage between the platen and the web during line-spacing operations.

To prevent the leading end of the composite web from slipping from the carriage, when withdrawn from the platen, provision may be made of suitable guiding means which may comprise two guides or rollers lightly spring-pressed, between which the forward end of the composite web extends.

The composite web between the carbon-carrier and the guiding means at the rear of

the carriage tends to sag, and thereby withdraw the leading end of the composite web from the rolls. To assist in preventing such action, provision may be made of an inclined table extending forwardly and upwardly from the rearmost position of the carbon-carrier to a position corresponding to the forward limiting position of the carbon-carrier, suitable space being left, however, between the forward edge of the table and the guide-rolls to accommodate the slack in the composite web.

Other features and advantages will hereinafter appear.

15 In the accompanying drawings,

Figure 1 is a view illustrating the invention as applied to an Underwood standard typewriter, the parts being shown in the positions occupied while typing is being effected.

20 Figure 2 is a view similar to Figure 1, but showing the parts in the positions occupied when the carbon-sheets and web-plies have been withdrawn from the platen preparatory to advancing the web-plies with reference to the interleaved carbons.

25 Figure 3 is a view similar to Figure 2, illustrating the gaging of the forward ends of the web-plies after being advanced with reference to the carbon-sheets, and the severing of the used portions of the web-plies when so advanced.

Figure 4 is a top view of the machine when set as in Figure 2.

30 35 Upon depression of character-keys (not shown), type-bars 11 are swung upwardly and rearwardly to cause types 12 thereon to strike against a platen 13 journaled by means of a platen-axle 14 in ends 15 of a 40 platen-frame 16 comprising a rear paper-table 17 and releasable rear and front feed-rolls 18 and 19, respectively. The platen frame 16 forms part of a carriage 20 traveling on a rear rail 21 fixed on a main frame 22. 45 Provision may be made of a work-holding finger 24 having at its free end a roll 25 to engage the platen adjacent the printing line.

50 55 The typing is effected upon superposed web-plies 26, usually provided with successive printed forms, the carbon copies on the plies back of the original being obtained by means of carbon-sheets 27 interleaved between the web-plies and attached at their rear ends to carbon-blades 28 mounted on usual stepped blocks 29 forming part of a carbon-carrier 30. When one set of forms has been typed, the web-plies and carbon-sheets may be relatively displaced, the used forms severed by a knife 31 and the typing 60 started on the next set of forms.

65 According to the present embodiment of the invention, the carbon-carrier 30 is mounted upon arms 32 fixed on a shaft 33, which, in turn, is journaled in the ends 34 of a secondary carriage 35 attached at the

upper edges of the ends 34 to a cross-bar 36 of the carriage 20 and supported at its lower edge by flanged rolls 37 running on a rail 38 fixed to brackets 39 secured by suitable means, such as screws 40, to the lower part 70 of the frame 22 at its rear. The rolls 37 may be pivoted on a cross-bar 41 joining the ends 34 of the secondary carriage 35, and may be held on the rail by fingers 42 engaging the rail on its lower side. 75

Fixed on shaft 33 is an arm 43 having a slot 44 to receive a rod 45 joining arms 46 fixed on a transverse shaft 47. The left-hand arm 46 is extended beyond the shaft to form a lever 48 with a second arm 49, 80 which is connected by a link 50 to a lever 51 pivoted to the frame 22 by means of a shouldered screw 52. Preferably, the lever 51 is provided with a handle 53 at its free end. When the handle is drawn to its forward 85 limiting position determined by a stop or pin 54, the arms 32 extend substantially horizontally, and, as shown in Figure 2, the position of the arms 46 is such as to hold the slotted arm 43 and carbon-carrier 30 firmly 90 in their Figure 2 positions. Similarly, when the handle 53 is moved rearward to its limiting position determined by a pin or stop 55, the arms 32 will be substantially vertical, as shown in Figure 1. In both of these 95 cases the arms 46 occupy substantially dead-center positions with reference to the arm 43. Preferably, the stops 54 and 55 are fixed in an arcuate bar 56 fixed on the frame 22 and provided with recesses 57 adjacent the 100 stops to receive a tapered detent pin 58 mounted in a detent-holder 59 on lever 51 and urged by a spring 60 to enter one of said recesses 57 when brought opposite the same. 105

The arms 32 are connected near their outer ends by a member 61 which forms the base of the carbon-carrier 30, and by a guide or rod 62 over which the web-plies 26 pass from a suitable source of supply to the carbon-carrier 30. The guide 62 may be provided with suitable side gages 63. As shown in Figures 1 and 2, the arms 32 are provided with projecting portions 64, which support the carbon-carrier base 61 in an inclined position, such that, when the carbon-carrier is positioned as shown in Figure 2, the base 61 will be substantially in alignment with an inclined table 65, and the web-plies 26 may be drawn through the carbon-carrier and over the table 65 to pass between guide-rolls 66, journaled in brackets 67 attached to the platen-frame 16. 110

From the rolls 66, the web-plies and carbon-sheets may, in case the carbon-carrier 125 has been advanced to its Figure 1 position, be passed downwardly over the rear paper-table 17 and between the platen 13 and the feed-rolls 18 and 19. Typing may then be effected, and the web-plies advanced from 130

one line-space position to another by means of finger-wheels 68 or line-space mechanism including a ratchet-wheel 69. Upon completion of the typing on one set of forms, the carbon-carrier 30 may be swung rearwardly to withdraw the web-plies and interleaved carbon-sheets from the platen 13 and feed-rolls 18 and 19, which have preferably been cast off, and, after the web-plies have been displaced with reference to the carbon-sheets and the used portions severed, the carbon-carrier may be swung forwardly to provide slack, and typing may be effected on the next set of forms, as hereininafter described.

The arms 32 are fixed on the shaft 33 just inside the ends 34 of the secondary carriage 35, and the table 65 must be of a width slightly less than the distance between the arms 32. To support the table 65, provision may be made of brackets 70 attached to the ends 34 of the secondary carriage, and, as shown in Figures 1 and 3, these brackets 70 are provided with offsets 71 to prevent interference with the arms 32 by the portions of the brackets 70 adjacent the table 65.

For gaging the web-plies when withdrawn from the platen and advanced relatively to the carbon-sheets, held in their rearward positions by the carbon-carrier 30, provision may be made of a gage 72 slidable on a guide or bar 73 and secured thereto at suitable positions by means of a set-screw 74. The bar 73 may be mounted on a cross-bar 75 connecting ends of arms 76 pivoted on the brackets 67, and an extension 77 of one of the arms 76 may be connected by a link 78 with one of two arms 79 carrying the knife 31 and mounted on pivots 80 in brackets 81 attached to the ends 15 of the platen-frame. Each of the arms 79 is provided with a stop or pin 82, so that when the gage-bar 73 and knife 31 are in their ineffective positions, Figure 1, the link 78 engages the stop 82 on the right-hand arm 79 and prevents further movement of the gage-bar and the knife under the urging of a spring 83, and, when the gage-bar 73 is swung to its Figure 2 position, the arms 79 come into engagement with the pins 82. At this time the gage-bar is substantially in alignment with the table 65 and the knife 31 is in effective position. For convenience in shifting the gage-bar 73 and the knife 31, provision may be made of a finger-piece 84 on the right-hand arm 79 or the bar 73 may be moved forwardly or rearwardly to effect such shifting.

It should be understood that the gage is positioned along the gage-bar 73 at a distance from the edge of the effectively positioned knife equal to the length of one of the forms on the web-plies. In machines of this kind, the portion of the web-plies above the printing line usually lies behind the severing knife, but with the present ar-

rangement the web-plies pass to the front of the knife, and are held against falling forward from the platen by means of the roll 25 and the paper-finger 24.

In practice, the web-plies 26 may be introduced into the machine when the carbon-carrier 30 is in its Figure 2 position, and, after the carbon-sheets 27 have been interleaved between the web plies, the composite web thus formed may be passed between the guide-rolls 66. The gage-bar 73 and knife 31 may then be shifted from their Figure 1 to their Figure 2 positions, and the leading edges of the web-plies 26 brought into engagement with the gage 72. The first set of forms is then severed by means of the knife, and, after swinging the carbon-carrier 30 to its Figure 1 position to produce a suitable amount of slack in the composite web, the leading end of the composite web is passed between the platen 13 and the feed-rolls 18 and 19.

Upon completion of the typing on the first set of forms passed around the platen, the feed-rolls 18 and 19 may be cast off and the handle 53 is then drawn forward to swing the carbon-carrier 30 to its Figure 2 position and withdraw the composite web from the platen. The leading ends of the web-plies 26 are then drawn forward and the gage-bar 73 and knife 31 swung to their effective positions shown in Figure 3. After gaging the leading ends of the web-plies 26 against the gage 72, the used form may be severed and the operation repeated as many times as there are sets of forms to be typed.

To assist in guiding the web from the roller 66 to the platen 13 there may be provided side-edge gages 85 which may be supported on the paper-table 17.

Variations may be resorted to within the scope of the invention, and portions of the improvements may be used without others.

Having thus described my invention, I claim:

1. In a typewriting machine of the class described, a platen around which web-plies and interleaved carbon-sheets may be fed, a movable carbon-carrier to which the rear ends of the carbon-sheets are attached, means operating the carbon-carrier to produce slack in the web-plies and interleaved carbon-sheets between the carbon-carrier and the platen to facilitate line-spacing, and means for holding said carrier locked when in position to permit shifting the web-plies relatively to the carbons.

2. In a typewriting machine of the class described, a platen around which web-plies and interleaved carbon-sheets may be fed, a movable carbon-carrier to which the rear ends of the carbon-sheets are attached, and means to shift the carbon-carrier to provide slack in the web-plies and interleaved carbon-sheets between the carbon-carrier and

the platen, said means effective to automatically lock said carrier in slack-producing position.

3. In a typewriting machine of the class described, a platen around which web-plies and interleaved carbon-sheets may be fed, means for holding the leading portions of said web-plies when withdrawn from the platen, a movable carbon-carrier to which the rear ends of the carbon-sheets are attached, means to shift the carbon-carrier to provide slack in the web-plies and interleaved carbon-sheets between the carbon-carrier and said holding means, and a table between the forward and rearward positions of the carbon-carrier, to support the web-plies and interleaved carbon-sheets when the carbon-carrier is in its rearward position and thereby prevent sagging of said web-plies which would tend to dislodge the leading portion thereof from said holding means.

4. In a typewriting machine of the class described, a platen around which web-plies and interleaved carbon-sheets may be fed, a movable carbon-carrier to which the rear ends of the carbon-sheets are attached, and means operating the carbon-carrier to produce slack in the web-plies and interleaved carbon-sheets between the carbon-carrier and the platen to facilitate line-spacing, and to withdraw the web-plies and interleaved carbon-sheets from the platen preparatory to effecting a relative shifting therebetween said means locking automatically to hold the carbon-sheets stationary during such shifting operation.

5. In a typewriting machine of the class described, a platen around which web-plies and interleaved carbon-sheets may be fed, a carriage for said platen, a shiftable carbon-carrier to which the rear ends of the carbon-sheets are attached, and a support over which the carbon-carrier is moved, said support being spaced from the rear of the carriage to accommodate in the opening thus formed slack in the web-plies and carbon-sheets produced by advancing the carbon-carrier from its rearward to its forward position.

6. In a typewriting machine of the class described, a platen, a carbon-carrier shiftable forwardly to produce slack between the carbon-carrier and the platen preparatory to typing, and rearwardly to withdraw web-plies and interleaved carbon-sheets from the platen preparatory to straightening them above the platen and advancing the web-plies with reference to the carbon-sheets, means for automatically locking the carrier when shifted to either of said positions, and supporting means for the web-plies and interleaved carbon-sheets extending forwardly from the rearmost position of the carbon-carrier.

7. In a machine of the class described, a platen, a traveling carriage therefor, a carbon-carrier, pivoted supporting arms for said carbon-carrier, and means for detaining said arms in raised or lowered positions, 70 said carbon-carrier being so supported on said arms that web-plies passing through the carbon-carrier extend in a direction to pass above the carriage, to permit gaging of the web-plies when withdrawn from the platen. 75

8. In a machine of the class described, a platen, a traveling carriage therefor, a carbon-carrier, pivoted supporting arms for said carbon-carrier, means for detaining said arms in raised or lowered position, said carbon-carrier being so supported on said arms that web-plies passing through the carbon-carrier extend in a direction to pass above the carriage, to permit gaging of the web-plies when withdrawn from the platen, and 80 an inclined table to support said web-plies forward of the rearmost position of the carbon-carrier.

9. In a machine of the class described, a platen, a carriage therefor, a frame on which the carriage travels, a rail fixed to the frame at the lower rear part thereof, a carriage-extension attached to the carriage and mounted on said rail to travel therealong, 90 a carbon-carrier, and a carbon-carrier frame pivoted on said extension.

10. In a machine of the class described, a platen, a carriage therefor, a frame on which the carriage travels, a rail fixed to the frame at the lower rear part thereof, a carriage-extension attached to the carriage and mounted on said rail to travel therealong, 100 a carbon-carrier, a carbon-carrier frame pivoted on said extension, a handle pivoted on the typewriter-frame, and connections between said handle and the carbon-carrier frame for shifting the same to advanced or retracted position, and to retain said carbon-carrier frame in such positions by placing certain portions of the connections in 110 dead-center relation.

11. In a machine of the class described, a platen, a carriage therefor, a frame on which the carriage travels, a rail fixed to the frame at the lower rear part thereof, a 115 carriage-extension attached to the carriage and mounted on said rail to travel therealong, a carbon-carrier, a carbon-carrier frame pivoted on said extension, a handle pivoted on the typewriter-frame, connections between said handle and the carbon-carrier frame for shifting the same to advanced or retracted position, and to retain said carbon-carrier frame in such positions by placing certain portions of the connections in 120 dead-center relation, and stops to determine the limiting position of said handle.

12. In a machine of the class described, a platen, a carriage therefor, a frame on 125

which the carriage travels, a rail fixed to the frame at the lower rear part thereof, a carriage-extension attached to the carriage and mounted on said rail to travel therealong, a carbon-carrier, a carbon-carrier frame pivoted on said extension, a handle pivoted on the typewriter-frame, connections between said handle and the carbon-carrier frame for shifting the same to advanced or retracted position, and to retain said carbon-carrier frame in such positions by placing certain portions of the connections in dead-center relation, stops to determine the limiting position of said handle, and detenting means to hold said handle in such limiting positions.

13. In a machine of the class described, a platen around which web-plies and carbon-sheets may be fed, a carriage, a frame on which the carriage travels, a rail extending across the lower back portion of the main frame, an extension of the carriage attached at its upper edge to the carriage, extending rearwardly and downwardly from the carriage, and mounted on said rail, a carbon-carrier, a carbon-carrier frame pivoted on said extension, and means to swing said carbon-carrier frame upwardly, adjacent the rear of the carriage, to furnish slack in the web-plies and carbon-sheets to permit typing, and to swing the carbon-carrier frame rearwardly to take up the slack and withdraw the web-plies from the platen preparatory to advancing the web-plies relatively to the carbon-sheets preparatory to severing the used portions of the web-plies.

14. In a typewriting machine of the class described, a platen around which a composite web of web-plies and interleaved carbon-sheets may be fed, a carriage for said platen, a carbon-carrier attached to said carbon-sheets and swingable upwardly and forwardly to provide slack in the composite web, and rearwardly and downwardly to withdraw the composite web from the platen, and guiding means on the carriage to restrain the leading end of the composite web from slipping from the carriage when withdrawn from the platen.

15. In a typewriting machine of the class described, a platen around which a composite web of web-plies and interleaved carbon-sheets may be fed, a carriage for said platen, a carbon-carrier attached to said carbon-sheets and swingable upwardly and forwardly to provide slack in the composite web, and rearwardly and downwardly to withdraw the composite web from the platen, guiding means on the carriage to restrain the leading end of the composite web from slipping from the carriage when withdrawn from the platen, and an inclined table extending upwardly from the rearward position of the carbon-carrier and supporting the composite web to keep it

from sagging and pulling out of said guiding means.

16. In a typewriting machine of the class described, a platen around which a composite web of web-plies and interleaved carbon-sheets may be fed, a carriage for said platen, a carbon-carrier attached to said carbon-sheets and swingable upwardly and forwardly to provide slack in the composite web, and rearwardly and downwardly to withdraw the composite web from the platen, guiding means on the carriage to restrain the leading end of the composite web from slipping from the carriage when withdrawn from the platen, an inclined table extending upwardly from the rearward position of the carbon-carrier and supporting the composite web to keep it from sagging and pulling out of said guiding means, a leading-edge gage, a knife, and means for concomitantly shifting said gage and said knife into substantial alignment with said inclined table.

17. In a machine of the class described, a carbon-carrier pivoted at the rear and lower part of the machine-frame, and a handle at the front of the frame for swinging said carbon-carrier from its lower rear position to its upper advanced position, and vice versa.

18. The combination with a typewriting machine having a platen to receive a composite web of web-plies and interleaved carbon-sheets, a carriage and a main frame, of a rail secured to the lower back part of said main frame, a secondary carriage having end frames secured at their upper ends to said carriage and mounted at their lower ends on said rail, and a carbon-carrier pivotally mounted on said secondary carriage to swing from a rearward position opposite the lower part of the secondary carriage to an advanced position adjacent the top of the carriage at its rear, to provide sufficient slack in the composite web preparatory to typing, and to withdraw said composite web from the platen after such typing to enable relative shifting of the web-plies and carbon-sheets preparatory to typing on the next unused set of forms.

19. In a machine of the class described, a platen, a platen-frame, means to direct a composite web of web-plies and interleaved carbon-sheets to the platen-frame, a gage to determine the amount of shifting of the web-plies with reference to the carbon-sheets, said gage being pivoted at the top and rear of the platen-frame, a knife pivotally mounted to be turned forwardly and downwardly against the top of the platen-frame, a spring to urge the knife in such direction, and a connection between said knife and said gage to cause both to move concomitantly to and from their effective positions.

20. In a machine of the class described, a platen, a platen-frame, means to direct a composite pack of web-plies and interleaved carbon-sheets to the platen-frame, a gage to determine the amount of shifting of the web-plies with reference to the carbon-sheets, a knife to sever the typed forms, said gage normally directed upwardly from said platen-frame adjacent the rear thereof and the knife positioned adjacent the front of the platen and behind the web-plies, and a connection between said gage and knife to cause them to move toward one another to their effective positions, said gage when thus moved being above the straightened composite web, and the knife positioned below said web.
21. In a continuous billing typewriting machine, the combination of a carriage, a platen around which a composite web comprising plies of work-sheets may be fed with interleaved carbon-sheets, a swingable carbon-carrier, to which the ends of the carbon-sheets are attached, pivoted on said carriage, and a finger-piece to swing said carbon-carrier rearwardly and downwardly to withdraw the composite web around the platen to free the carbon-sheets from the platen and bring them to straightened-out inclined position, so that the work-sheets may be drawn forwardly over the platen to shift them relatively to the carbon-sheets.
22. In a continuous billing typewriting machine, the combination of a carriage, a platen around which a composite web comprising plies of work-sheets may be fed with interleaved carbon-sheets, means at the rear of the platen to withdraw the composite web therearound to free it therefrom and to bring the carbon-sheets to a straightened-out position inclined downwardly behind the platen, so that the work-sheets may be drawn forwardly and upwardly to shift them relatively to the carbon-sheets, a gage-bar for the leading end of the web as the latter extends forwardly over the platen, a knife, and means to move the knife to position beneath said work-sheets to sever the typed portions thereof, said knife being normally positioned behind said web and adjacent the front of the platen.
23. In a continuous billing typewriting machine, the combination of a carriage, a platen around which a composite web comprising plies of work-sheets may be fed with interleaved carbon-sheets, means to establish a loose loop of composite web at the rear of the platen or to withdraw said web around the platen to free it therefrom and to bring the web to a straightened-out inclined position behind the platen, so that the work-sheets may be drawn forwardly to shift them relatively to the carbon-sheets, a gage mounted on a gage-bar and swingable downwardly toward said straightened-out web to determine the amount of shifting of the work-sheets, and a knife moved by said gage from a normal position adjacent the platen to a position beneath the inclined web during a severing operation.
24. In a continuous billing typewriting machine, the combination of a carriage, a platen around which a composite web, comprising plies of work-sheets may be fed with interleaved carbon-sheets, a carbon-carrier to which the ends of the carbon-sheets are attached, said carbon-carrier being pivotally mounted on the carriage, a finger-piece to swing said carbon-carrier rearwardly and downwardly to withdraw the composite web around the platen to free it from said platen and bring that portion of the web containing the carbon-sheets to a straightened-out inclined position to extend upwardly and forwardly from the back of the machine, and a gage in the path of the web to determine the extent of shifting of the work-sheets.
25. In a continuous billing typewriting machine, the combination of a carriage, a platen around which a composite web comprising plies of work-sheets may be fed with interleaved carbon-sheets, and means at the rear of the platen to withdraw the composite web around the platen to free the carbon-sheets from the platen and to bring them to a straightened-out inclined position, so that the work-sheets may be drawn upwardly and forwardly over the platen to shift them relatively to the carbon-sheets.
26. In a continuous billing typewriting machine, the combination of a carriage, a platen around which a composite web comprising plies of work-sheets may be fed with interleaved carbon-sheets, a swingable carbon-carrier at the rear of the platen to which the carbon-sheets are attached, and means to swing said carbon-carrier to withdraw the composite web around the platen to free it from the platen and bring the carbon-sheets to a straightened-out position, so that the work-sheets may be drawn forwardly over the platen to shift them relatively to the carbon-sheets.
27. In a continuous billing typewriting machine, the combination of a carriage, a platen around which a composite web, comprising plies of work-sheets may be fed with interleaved carbon-sheets, a carbon-carrier to which the ends of the carbon-sheets are attached, said carbon-carrier being pivotally mounted on the carriage, a finger-piece to swing said carbon-carrier rearwardly and downwardly to withdraw the composite web around the platen to free it from said platen and bring that portion of the web including the carbon-sheets to a straightened-out inclined position to extend upwardly and forwardly from the back of the machine, a gage in the path of the web to determine the ex-

tent of shifting of the work-sheets, and a knife over the top of which the work-sheets may be drawn to said gage, and by which the typed sections of the work-sheets may be severed by drawing said typed sections downwardly towards the platen.

28. In a continuous billing typewriting machine, the combination of a carriage, a revolute platen on said carriage around which continuous work-sheets may be fed with interleaved carbon-sheets, an extension on said carriage, and a reciprocable carbon-carrier pivoted on said extension and movable to and away from said platen.

29. In a continuous billing typewriting machine, the combination of a carriage, a revolute platen on said carriage around which continuous work-sheets may be fed with interleaved carbon-sheets, a main frame on which the carriage travels, a guide-rail secured to said main frame, a sub-carriage to travel on said guide-rail and connected to said first-named carriage, and a reciprocable carbon-carrier comprising a rock-shaft pivoted on said sub-carriage, an arm on said rock-shaft, a bail pivoted on said main frame to engage said arm, and a finger-piece to actuate said bail.

30. In a continuous billing typewriting machine, the combination of a carriage, a revolute platen on said carriage around which continuous work-sheets may be fed with interleaved carbon-sheets, an extension on said carriage, a reciprocable carbon-carrier pivoted on said extension, and an actuator engaging with said carbon-carrier to operate the latter, said actuator being so arranged with respect to the carbon-carrier as to lock the latter in its normal position and in its operative position.

31. In a continuous billing typewriting machine, the combination of a carriage, a revolute platen on said carriage around which continuous work-sheets may be fed with interleaved carbon-sheets, a main frame on which said carriage travels, a downward extension behind said main frame and on said carriage, and a carbon-carrier pivoted on said extension, said carbon-carrier normally occupying a vertical position and swingable rearwardly and downwardly to a horizontal position.

32. In a continuous billing typewriting machine, the combination of a carriage, a revolute platen on said carriage around which continuous work-sheets may be fed with interleaved carbon-sheets, a main frame on which said carriage travels, a downward extension behind said main frame and on said carriage, a carbon-carrier pivoted on said extension, said carbon-carrier normally occupying a position close to the main frame, and a finger-piece to actuate said carbon-carrier to swing it rearwardly from said main frame.

33. In a continuous billing typewriting machine, the combination of a carriage, a revolute platen on said carriage around which continuous work-sheets may be fed with interleaved carbon-sheets, an extension on said carriage, a reciprocable carbon-carrier pivoted on said extension and movable to and away from said platen, side-edge guides, for said work-sheets, on said carbon-carrier, and side-edge guides on said carriage for said work-sheets.

34. In a continuous billing typewriting machine, the combination of a carriage, a platen around which a continuous composite web comprising plies of work-sheets with interleaved carbon-sheets may be fed, and means to withdraw the web about the platen to free it therefrom and bring it to an inclined position downwardly from said platen, so that the leading portion of the composite web is inclined upwardly above said platen and may be readily grasped and advanced relatively to the carbon-sheets.

35. In a continuous billing typewriting machine, the combination of a carriage, a platen around which a continuous composite web comprising plies of work-sheets with interleaved carbon-sheets may be fed, means behind the platen to withdraw the web around the platen to free it therefrom and bring it to an inclined position, so that the work-sheets may be grasped and drawn forwardly over the platen to shift them relatively to the carbon-sheets, and a gage to determine the extent of shifting of the work-sheets.

36. In a continuous billing typewriting machine, the combination of a carriage, a platen around which a continuous composite web comprising plies of work-sheets with interleaved carbon-sheets may be fed, means to withdraw the web about the platen to free it therefrom and bring it to an inclined position, so that the work-sheets may be grasped and advanced relatively to the carbon-sheets, and means to hold the carbon-sheets locked during the shifting of the work-sheets.

37. In a continuous billing typewriting machine, the combination of a carriage, a platen around which a continuous composite web comprising plies of work-sheets with interleaved carbon-sheets may be fed, a carbon-carrier to withdraw the composite web about said platen and free it therefrom and bring said web to a straightened-out position, so that the work-sheets may be advanced relatively to the carbon-sheets, and locking means co-operating with the carbon-carrier to hold the carbon-sheets while the work-sheets are being advanced.

38. In a continuous billing typewriting machine, the combination of a carriage, a platen around which a continuous composite web comprising plies of work-sheets with

- interleaved carbon-sheets may be fed, means to withdraw the web about the platen to free it therefrom and bring it to an inclined position, so that the work-sheets may be grasped and advanced relatively to the carbon-sheets, and a knife over which the work-sheets may be advanced and against which the work-sheets may be drawn towards the platen to sever the typed portions thereof.
39. In a continuous billing typewriting machine, the combination of a carriage, a platen around which a continuous composite web comprising plies of work-sheets with interleaved carbon-sheets may be fed, means to withdraw the web about the platen to free it therefrom and bring it to an inclined position, so that the work-sheets may be grasped and advanced relatively to the carbon-sheets, a gage-bar beneath which said web may be advanced, an adjustable gage on said gage-bar to determine the extent of shifting of said work-sheets, and a knife over which the work-sheets may be advanced and against which the work-sheets may be drawn towards the platen to sever the typed portions thereof.
40. In a continuous billing typewriting machine, the combination of a carriage, a platen on said carriage around which a composite web comprising continuous work-sheets with interleaved carbon-sheets may be fed, means including a pivoted carbon-carrier to assist in conditioning the web so that there may be a relative shifting between the carbon-sheets and the work-sheets, and means to lock the carbon-carrier during advance of the web at the carbon stripping operation.
41. In a continuous billing typewriting machine, the combination of a carriage, a platen on said carriage around which a composite web comprising continuous work-sheets with interleaved carbon-sheets may be fed, means including a pivoted carbon-carrier to assist in conditioning the web so that there may be a relative shifting between the carbon-sheets and the work-sheets, said carbon-carrier being pivoted on said carriage, an independently mounted finger-piece, a connection comprising operating elements between said finger-piece and said carbon-carrier by which the carbon-carrier may be operated by the finger-piece, and means to lock the carbon-carrier in its extreme position.
42. In a continuous billing typewriting machine, the combination of a carriage, a platen on said carriage around which a composite web comprising continuous work-sheets with interleaved carbon-sheets may be fed, means including a pivoted carbon-carrier to assist in conditioning the web so that there may be a relative shifting between the carbon-sheets and the work-sheets, said carbon-carrier comprising two arms pivoted at their ends, means comprising a slot at the ends of said arms, a bell-crank to engage in said slot, and a finger-piece to actuate said bell-crank.
43. In a continuous billing typewriting machine, the combination of a carriage, a platen on said carriage around which a composite web comprising continuous work-sheets with interleaved carbon-sheets may be fed, means including a pivoted carbon-carrier to assist in conditioning the web so that there may be a relative shifting between the carbon-sheets and the work-sheets, said carbon-carrier comprising two arms, a rock-shaft to which said arms are secured, an intermediate arm on said rock-shaft, said intermediate arm having a slot therein, a bell-crank to engage in said slot, a link connected to said bell-crank, and a pivoted finger-piece connected to said link to actuate said bell-crank and consequently the carbon-carrier.
44. In a continuous billing typewriting machine, the combination of a carriage, a platen around which a composite web comprising plies of work-sheets with interleaved carbon-sheets may be fed, a carbon-carrier to which the ends of the carbon-sheets are attached, said carbon-carrier being pivotally supported, and a finger-piece to swing said carbon-carrier away from the platen to condition the web so that there may be effected a relative shifting between the carbon-sheets and the work-sheets after the carbon-carrier has been operated.
45. In a continuous billing typewriting machine, the combination of a carriage, a platen around which a composite web comprising plies of work-sheets with interleaved carbon-sheets may be fed, and a carbon-carrier to which the ends of the carbon-sheets are attached, said carbon-carrier being pivoted at the rear of said carriage to draw the web around the platen to free the carbon-sheets from said platen preparatory to a relative shifting between the carbon-sheets and the work-sheets.
46. In a continuous billing typewriting machine, the combination of a carriage, a platen around which a composite web comprising plies of work-sheets may be fed with interleaved carbon-sheets, a carbon-carrier to which the ends of the carbon-sheets are attached, said carbon-carrier being pivoted at the rear of said platen to draw the web around the platen to free the carbon-sheets from said platen preparatory to a relative shifting between the carbon-sheets and the work-sheets, and means to lock the carbon-carrier in its operated position to hold the carbon-sheets while the work-sheets are being shifted.
47. In a typewriting machine, the combination of a rotatable platen, a letter-feeding carriage therefor, a swingable support at the introductory side of the platen for

supporting the rear end of a composite loop of multiple ply work-web and carbons, the front end of the web being connected with the platen during typing operations, said support swingable rearwardly from the platen to straighten out the web and then withdraw the same from the control of the platen, and means for supporting the leading portion of said web when thus withdrawn from said platen.

48. In a typewriting machine, the combination of a rotatable platen, a letter-feeding carriage therefor with a swingable support at the introductory side of the platen for supporting the rear end of a composite loop of multiple ply work-web and carbons, the front end of the web being normally con-

nected with the platen, said support movable rearwardly from the platen to straighten out the loop and then withdraw the web from the control of the platen, and a pair of rolls for supporting the free end of said web when thus withdrawn from the platen.

49. A typewriting machine having a platen and a carriage, a carbon-holder mounted adjacent the rear of the machine to swing forwardly or rearwardly relatively to the platen, a handle associated with said carbon-holder to actuate the same, and means cooperating with said handle and said holder to automatically lock the holder in either of its extreme positions.

JOHN WALDHEIM.
